[57] CLAIM

The ornamental design for a lamp base, as shown and
described.

DESCRIPTION

FIG. 1 is a top plan view of a lamp base showing our
new design;

FIG. 2 is a side elevational view thereof, the opposite
side being identical thereto;

FIG. 3 is a bottom plan view thereof;

FIG. 4 is a top plan view of a second embodiment of the
lamp base;

FIG. 5 is a side elevational view thereof, the opposite
side being identical thereto;

FIG. 6 is a bottom plan view thereof.

FIG. 2

FIG. 1

FIG. 3

FIG. 5

FIG. 4

FIG. 6
